UNITED STATES PATENT OFFICE.

ALFRED L. MADISON, OF NEW YORK, N. Y., ASSIGNOR TO WILLCOX AND GIBBS SEWING MACHINE COMPANY, OF NEW YORK, N. Y., A CORPORATION OF NEW YORK.

GUARD FOR SEWING-MACHINE TAKE-UPS.

1,191,015.

Specification of Letters Patent. Patented July 11, 1916.

Application filed February 26, 1915. Serial No. 10,744.

To all whom it may concern:

Be it known that I, ALFRED L. MADISON, a citizen of the United States of America, residing in the city of New York, county 5 and State of New York, have invented a certain new and Improved Guard for Sewing-Machine Take-Ups, of which the following is a specification.

My present invention relates more particularly to a special improvement in the 10 Willcox and Gibbs high-speed sewing machine with rotary take-up forming the subject of the Letters Patent of Borton, No. 572,090, dated November 24, 1896, and Brush and Borton, No. 675,438, dated June 4, 1901. In the said machine there is attached to the left hand end of the rotary shaft in the head of the machine a take-up in the form of a wheel, which, as shown in Patent No. 15 675,438, has to be made with openings in it for lightness, because of the high speed at which the machine is run,—say 3000 stitches a minute.

The object of my invention is to provide 20 this rotary take-up with guard means to prevent the operator from accidentally getting her fingers or hair caught in the wheel, while at the same time not interfering with the easy threading of the take-up or other 25 part of the machine or the removal of a broken thread from the take-up, and this without removing the guard from its normal position.

In the accompanying drawing, Figure 1 30 is an elevation of the left-hand end of the machine head, provided with the preferred form of improvement; Fig. 2 is a side view of my improved guard and the supporting band, detached from the machine; Fig. 3 is 35 a corresponding view of the other side of the same guard and band; and Fig. 4 is an enlarged view of the left hand end of the machine with the take-up, its band and the guard in section.

40 A is the sewing machine head, which in suitable bearings carries the rotary shaft B (see dotted lines in Fig. 4) and to the left hand end of this shaft is secured as by a steady pin 10 and fastening screw 11, the 45 rotary take-up wheel C, which is constructed substantially as described in said Patent No. 675,438. The wheel comprises a pair of spider disks 12 each having peripheral rings and central areas united by radial arms X, the spaces 13 between which form

openings into which the operator's fingers may accidentally be inserted or stray locks of hair find their way and become entangled in the rapidly driven mechanism. The two disks are united by a screw 14 passing through a distance thimble 15 (Fig. 4) and the outer disk has a central aperture 23. Around the peripheries of the disks is a band E pivoted at 16 to a short sleeve 17 on the stem 18 on the sewing machine head A, 60 while a flange 28 on the band is secured by screw 29 to the face of the head A. As seen in Fig. 3, the band E is cut away at 19 to facilitate the introduction of the thread between the two disks of the rotary take-up. 70

The parts so far described are substantially the same as heretofore used and as disclosed in the patents hereinabove mentioned.

Over the otherwise open face or end of the rotary take-up I provide a guard in the form of a disk D, which I secure in a fixed position by suitable means, as a pair of lugs 20, 20, at its lower rear edge, attached by screws or otherwise to the band E. By the described mode of attachment, a clearance 21 (Figs. 2 and 4) is left between the disk D and band E, all the way around except at 20, 20, for the free introduction and play of the thread in the take-up and for the proper threading of the needle N. This guard disk D is provided with a central opening 22 opposite a central opening 23 in the outer disk of the take-up (Fig. 4) in order to permit the operator to pick out broken 80 thread ends. Neither the presence of this central opening 22 nor the clearance 21 will interfere with the performance of the function of the disk D guarding against the catching of the operator's fingers or hair in 85 the rapidly revolving take-up. 90

I claim as my invention:

1. In a sewing machine, a rotary take-up having an exposed spider disk with central opening, in combination with a fixed guard disk mounted over the open end of the take-up and having a closed area coextensive with the open frame area of the spider disk to prevent accidental contact with the spider arms but having a central opening registering with the central opening of the spider disk through which thread ends may be picked up. 100

2. In a sewing machine, a rotary take-up having an inner and an outer spider disk 105

spaced apart but secured together, the outer spider disk having a central opening while the inner disk has a central closed dia-
phragm, in combination with a fixed guard
disk mounted beyond the exposed face of
the take-up and having a closed area coex-
tensive with the open frame area of the
spider disks to prevent accidental contact
with the spider arms and having a central
opening registering with the central open-
ing of the outer spider disk through which
thread ends may be picked up.

3. In a sewing machine, a rotary take-up
having an exposed spider disk with sur-

rounding guard band pivoted to the ma- 15
chine frame, in combination with a fixed
guard disk secured to said band and over-
lying the exposed face of the spider disk
and having a closed area coextensive with
the open frame area thereof to prevent acci- 20
dental contact with the spider arms.

In testimony whereof I have signed my
name to this specification, in the presence of
two subscribing witnesses.

ALFRED L. MADISON.
